UNITED STATES PATENT OFFICE.

CHARLES BRYANT MACDOUGALL, OF SEATTLE, WASHINGTON.

DESIGN FOR A LIGHTING BOWL.

Application filed February 13, 1923. Serial No. 5,163. Term of patent 3½ years.

To all whom it may concern:

Be it known that I, CHARLES BRYANT MACDOUGALL, a citizen of the United States of America, residing at the city of Seattle, in the county of King and State of Washington, have invented a new, original, and ornamental Design for Lighting Bowls, of which the following is a specification, refer-

ence being had to the accompanying drawing, forming part thereof.

The figure is an elevation of the lighting bowl, showing my new design.

I claim:

The ornamental design for a lighting bowl, as shown.

C. BRYANT MACDOUGALL.
